UNITED STATES PATENT OFFICE

160,245

ELECTRIC SCORER FOR SHUFFLEBOARD
GAMES

Arthur H. Bouterious, Oakland, Calif., assignor to
Mills Sales, Inc., Oakland, Calif., a corporation
of Nevada

Application June 26, 1948, Serial No. 147,212
Term of patent 3½ years

(Cl. D34—5)

To all whom it may concern:

Be it known that I, Arthur H. Bouterious, a citizen of the United States and a resident of Oakland, county of Alameda, and State of California, have invented a new, original, and ornamental Design for an Electric Scorer for Shuffleboard Games, of which the following is a specification, reference being had to the accompanying drawing, forming part thereof.

Figure 1 is a front elevational view of the scorer showing my new design.

Figure 2 is a side elevational view of the scorer.

The dominant features of my design reside in that portion shown in full lines in the drawing.

I claim:

The ornamental design for an electric scorer for shuffleboard games, substantially as shown and described.

ARTHUR H. BOUTERIOUS.
